United States Patent

Des. 241,500
Patented Sept. 21, 1976

241,500

TORQUE LIMITING DEVICE

Ralph R. Leonard, 1822 S. 266th Place,
Kent, Wash. 98031

Filed Aug. 7, 1975, Ser. No. 602,919

Term of patent 14 years

Int. Cl. D8—05

U.S. Cl. D8—24

Fig. 1

Fig. 2

Fig. 3

Fig. 4

Fig. 5

FIG. 1 is a perspective view of a torque limiting device showing my new design;

FIG. 2 is a further perspective view;

FIG. 3 is a front elevational view;

FIG. 4 is a top plan view; and

FIG. 5 is a bottom plan view thereof.

I claim:

The ornamental design for a torque limiting device, as shown and described.
